UNITED STATES PATENT OFFICE.

WILLIAM McCABE AND ROBERT McCABE, OF MEADVILLE, PENNSYLVANIA.

BASE ROCKING-CHAIR.

SPECIFICATION forming part of Letters Patent No. 258,239, dated May 23, 1882.

Application filed January 17, 1882. (Model.)

To all whom it may concern:

Be it known that we, WILLIAM McCABE and ROBERT McCABE, citizens of the United States, residing at the city of Meadville, in the county of Crawford and State of Pennsylvania, have invented a new and useful Base Rocking-Chair, of which the following is a specification.

Our invention relates to improvements in "rocking-chairs" whose rockers set on a base and are attached thereto in a secure manner, and yet so constructed that they will rock freely on their base without noise or friction. We attain this object by the mechanism illustrated in the accompanying drawings, in which—

Figure 1 is a back view, and Fig. 2 a sectional side view, of our rocking-chair.

E, Figs. 1 and 2, represents the base, constructed in the usual form of bases of rockers. F is a strong bar of wood that connects the back ends of the sides of the base together; R, a rung that connects the front ends together. On the bar F are two semicircular springs, of flat steel or other suitable metal, secured firmly thereto by screws or screw-bolts, (see Fig. 2,) which shows one of them, there being another like it on the other side of the chair.

O is a bar of wood or metal attached to the upper part of the spring by screws or bolts, with a notch in the under side of the end thereof to hook or drop on a pin, P. This pin P is attached to the rocker B, which rests on the base E, and thereby prevents the rocker B from having a lateral motion on the base when in use.

H is an arm of metal screwed on the rocker B, and projecting down toward the floor in side of the sides of the base, as shown in the drawings, Fig. 2. This arm has a hook on its lower end, which "stops" against a pin, S, when the rocker is tipped back as far as it is desired to have it. The pin P is attached to this arm, as shown in the drawings.

In the construction of a chair in such a manner as to permit it to rock freely and at the same time to prevent any lateral or sliding motion on the base, it is found necessary to have the bar O attached to the spring made of some rigid material—that is, it is found by experiment that it would not do to extend the semicircular spring itself forward to hook on the pin P, as it would bend its whole length, causing the rocker to slide on the base. This difficulty is obviated by having the bar O of rigid material and attached to the semicircular spring G. This allows the chair to rock freely without any friction or lateral motion. The dotted line in the drawings shows the position of the spring G, hook H, and bar O when the chair is rocked or tipped back as far as desired.

C is the front of the frame of the seat, D the arm, and A the side of the chair-frame.

What we claim as new is—

1. In a base rocking-chair, a spring attached to the base and projecting forward and provided with an inelastic arm having a slot therein, in combination with a rocking seat having a pin for holding the inelastic arm in place, and a downwardly-projecting hooked arm which catches upon a pin on the base when the chair has been tilted.

2. In a base rocking-chair, a base having a curved spring attached to its rear rung, and having an inelastic arm provided with a slot formed above the base, in combination with a rocking seat having a pin for holding the inelastic arm in place, and a downwardly-projecting hooked arm which catches upon a pin fixed to the base when the chair has been tilted, all arranged substantially as described.
